MOLDED POOL WITH INTEGRALLY MOLDED SLIDE

Ascher Chase, Norfolk, Va., assignor to General
Foam Plastics Corp., Norfolk, Va.

Filed Sept. 22, 1970, Ser. No. 25,144

Term of patent 14 years

Int. Cl. D21—01

U.S. Cl. D34—5

FIG. 1

FIG. 3

FIG. 1 is a perspective view of a molded pool with integrally molded slide embodying my new design;

FIG. 2 is a plan view of the pool shown in FIG. 1; and

FIG. 3 is a side elevational view of the pool shown in FIG. 1.

I claim:

The ornamental design for a molded pool with integrally molded slide, substantially as shown.
